UNITED STATES PATENT OFFICE.

RUDOLPH M. GRIEBEL, OF SEATTLE, WASHINGTON.

GAME-BOARD.

1,370,017.

Specification of Letters Patent.

Patented Mar. 1, 1921.

Application filed April 23, 1920. Serial No. 375,915.

To all whom it may concern:

Be it known that I, RUDOLPH M. GRIEBEL, a citizen of the United States, residing at Seattle, in the county of King and State of Washington, have invented certain new and useful Improvements in Game-Boards, of which the following is a specification.

This invention relates to improvements in games; and has for its object the provision 10 of a game-board of simple design with which an extremely interesting and attractive game may be played.

The invention consists in the novel construction of a game-board and in the adaptation and combination of parts, details and accessories, as will be fully described in the following specifications, illustrated in the accompanying drawings, and finally set forth in the appended claim.

20 In said drawings, Figure 1 is a plan view of a game-board embodying my invention. Fig. 2 is a view in vertical cross-section of the same. Fig. 3 is a fragmentary perspective view, showing one of the details of the invention more fully.

Referring to said views, wherein similar parts in the several views are indicated by similar reference numerals, the reference number 10 designates the plane bottom of 30 a rectangular game-board formed of cardboard or other similar light material, and 11 indicates the vertical side walls inclosing a playing compartment 12.

A plurality of shallow cups 13, preferably 35 formed of wood, fiber or other suitable composition, are cemented to the bottom and arranged symmetrically within said compartment. Said cups may be arranged in any symmetrical manner having spaces between the cups and between the cups and the side walls 11 to allow the ball 15 to run freely about the playing compartment. Adjacent each cup a so-called T indicated by 16, is fixedly secured to the board-bottom. Said

40 T's are intended to afford a position for the ball when attempting a "stroke" for its respective cup. Said T's may be of any suitable form, and are shown as ridges molded or secured on the bottom 10, and are of some- 45 what obtuse V-shaped configuration. Said T's are provided for each of said cups, re- 50 spectively, and are arranged symmetrically

with respect thereto at convenient distances so that the ball may be vaulted from the T into the respective cup. 55

Said ball 15 completes the playing paraphernalia of the game, and may be formed of solid rubber, fiber, wood or other suitable composition. The radii of the ball should be less than that of the arc described by the 60 curvature of the cups 13 in radial cross-sections, to admit of the ball playing in and out of the cups freely.

The play of the game may be described as follows, although it will be understood 65 that the manner of play is not proscribed exactly and the game-board lends itself very readily to many variations of play.

The play of the game is to use the least number of attempts to toss the ball into each 70 of the cups, successively. The ball is rolled or placed in the T 16 pertaining to the respective cup, and the board is given a short quick jerk that will toss the ball in the air and the board is manipulated to catch the 75 ball in the proper cup. The strokes, or times the ball is tossed in the air, are counted and the player having the lowest number of strokes in all of the holes wins the game.

As additional features and which may be 80 utilized in varying the style of play or method of scoring, the cups 5 may be painted or otherwise colored in different and distinguishing colors (not indicated on the drawing) and they may be further characterized by a number, as 17, indicating the 85 order of rotation with which the several cups are to be played, or otherwise.

While the game-board and apparatus is very simple, considerable skill and manual 90 dexterity is required. The rules and manner of play may be varied and the interest and variety of play kept up indefinitely.

Having described my invention, what I claim, is—

In a game-board of the class described, a game-board having a plane bottom, a plurality of ball-receiving cups spaced apart and elevated above said bottom, a ball adapted to coöperate with said cups in the play 100 of the game, and a plurality of V-shaped T's spaced from the cups, respectively.

Seattle, Washington, April 17, 1920.

RUDOLPH M. GRIEBEL.
